UNITED STATES PATENT OFFICE.

RICHARD M. BEDELL, OF BROOKLYN, NEW YORK, ASSIGNOR TO MERGENTHALER LINOTYPE COMPANY, A CORPORATION OF NEW YORK.

TYPOGRAPHICAL CASTING-MACHINE.

1,129,159.

Specification of Letters Patent. Patented Feb. 23, 1915.

Application filed May 3, 1913. Serial No. 765,202.

To all whom it may concern:

Be it known that I, RICHARD M. BEDELL, a citizen of the United States, residing at Brooklyn, in the county of Kings and State 5 of New York, have invented certain new and useful Improvements in Typographical Casting-Machines, of which the following is a specification, reference being had therein to the accompanying drawings.

10 My invention relates to typographical casting machines, such for instance as linotype machines of the general character set forth in Letters Patent of the United States, No. 436,532, to O. Mergenthaler, wherein 15 the slug or linotype is cast in a slotted mold and is then delivered therefrom by a reciprocating ejector blade, which advances through the mold from the rear, forcing the slug before it through the trimming mechanism to the receiving galley at the front of the machine. The ejector blade is connected to the front end of a horizontally movable slide, the construction being such that it 20 may be readily detached therefrom to permit the substitution of another of different 25 dimensions.

In the commercial linotype machine, the ejector slide is mounted on a second slide which carries the mold wheel at its outer 30 end. In order to effect certain adjustments and for various other purposes not necessary to state herein, it is frequently necessary to draw the ejector slide manually forward to bring it to a convenient position for 35 the desired manipulation. In the past, this result has been accomplished in a variety of ways. For example, in order to advance the blade to the required position, the operator has left his place at the machine and turned 40 the actuating cam and connected parts by hand; or he has disconnected the link from the ejector lever by the removal of the connecting pin; or in another instance the ejector slide has been provided with a movable 45 latch to permit its disconnection from the link. In my present form, I provide improved means whereby the link may be readily connected to or disconnected from the actuating lever at will, the parts being 50 so constructed and arranged as to prevent their accidental displacement both in operative and inoperative position.

In the accompanying drawing, I have shown my invention in preferred embodiment and by way of example, and as adapt-

ed to the linotype machine, but obviously many changes and variations may be made therein, and in its mode of application, which will still be comprised within its spirit. Generally speaking, I desire it to be 60 understood that I do not limit myself to any specific form or embodiment, except in so far as such limitations are specified in the claims.

In the accompanying drawing; Figure 1 65 is a side elevation of the mold wheel, mold slide, ejector slide, and its actuating link and lever, having my improvement embodied therein; Fig. 2 is an enlarged detail, illustrating the improved latch in operative condition; Fig. 3 is a similar view of the latch in detached position; and Fig. 4 is a section on the line 4—4 of Fig. 2.

The mold slide A carries the mold wheel B, and also the ejector slide C, which is 75 reciprocated with relation thereto by the actuating link D and ejector lever E in the usual manner, as in the ordinary commercial linotype machine, or as illustrated for instance in numerous Letters Patent of the 80 United States, such as No. 945,609 to J. R. Rogers. The link D is connected to the lever E by the pin F mounted in the latter, and to permit the ready engagement and disengagement of the parts for the purposes 85 previously indicated, I have provided the link with connecting means which are now to be described. The link D is formed at its rear end with the vertical notch D' to engage the pin F. The end of the link is also 90 provided with the relatively movable latch G formed with the horizontal notch J which also engages the pin F, and whereby the link is securely held in relation thereto, when the parts are in their operative condition. The 95 end of the link D is bifurcated, (see Fig. 4), and the latch G is located therein, it being pivotally mounted upon the transverse pin H which passes through the longitudinal slot G', this arrangement permitting two 100 movements of the latch with reference to the link, pivotally about the pin and also longitudinally to the extent permitted by the length of the slot.

The latch G is formed at its inner end 105 with the inclined or beveled surface K, and the link D with the correspondingly inclined or beveled surface L, a spring M being also provided, connected at one end to the latch and at its other end to the link, in such man- 110

ner that when the parts are in operative condition (see Fig. 2), the spring holds the two surfaces in contact and thereby prevents the accidental disengagement of the 5 parts. At this time, the end of the link D is held against vertical displacement by the engagement of the horizontal slot J of the latch G with the pin F, and the end of the slot G' is in close relation to the pivotal pin 10 H. This position of the parts continues until the latch G is moved longitudinally (see Fig. 3), and the other end of the slot G' is brought into relation to the pin H, at which time the disengagement of its notch 15 J from the pin F and the separation of the surfaces K and L permits the pivotal movement of the latch, when the end of link D may be elevated to free its notch D' from the pin F. The ejector slide C may now be 20 moved at will for the purposes of blade substitution or otherwise.

It is to be noted that due to the combined longitudinal and pivotal movements of the latch with reference to the link, the parts 25 when shifted either to operative or inoperative position, pass center and are then securely held in substantially the same manner as in the well-known jackknife joint. Moreover, the spring M acts to move the 30 parts to their final position when manually started in either direction. For instance, if the latch be in the locking position, as shown in Fig. 2, and if it be moved longitudinally and then slightly tilted upward, the 35 spring immediately snaps it to the unlocking position, as shown in Fig. 3. Or if from the latter position the latch be tilted downward, the spring draws it home and restores it to the locking position.

40 As previously stated, I have shown my invention only in preferred form and by way of example, but obviously many modifications and variations therein, as well as in its mode of application, will suggest themselves to those skilled in the art without departure from its scope.

Having thus described my invention, its construction and mode of operation, what I 50 claim and desire to secure by Letters Patent of the United States, is as follows:

1. In a linotype machine, the combination of the ejector slide, its actuating lever, and the intermediate connecting link, the lever being provided with the pin F to engage the 55 link, and the link carrying the movable latch G which engages beneath the pin F and thus serves to prevent the disengagement of the link from the pin.

2. In a linotype machine, the combination 60 of the ejector slide, its actuating lever, and the intermediate connecting link, the lever being provided with the pin F to engage the

link, and the link carrying the movable latch G formed with the slot J to straddle the pin and thus prevent the disengagement of the 65 link from the pin.

3. In a linotype machine, the combination of the ejector slide, its actuating lever, and the intermediate link, the lever being provided with the pin F, and the link being 70 formed with the vertical slot D' to engage the pin, and provided with the movable latch G formed with the horizontal slot J to engage the pin.

4. In a linotype machine, the combination 75 of the ejector slide C, link D, and actuating lever E, the said lever being provided with the pin F to engage the link, and the link being provided with the pivotally and longitudinally movable latch G to engage said 80 pin.

5. In a linotype machine, the combination 85 of the ejector slide C, link D, and actuating lever E, the said lever being provided with the pin F, and the link being formed with 90 the vertical slot D' to engage the pin and provided with the longitudinally and pivotally movable latch G formed with the notch J to engage said pin.

6. In a linotype machine, the combination 95 of the ejector slide C, link D, and actuating lever E, the said lever being provided with the pin F to engage the link, and the link being provided with the pivotally and longitudinally movable latch G to engage said 100 pin, together with the spring M to hold the latch in both operative and inoperative position.

7. In a linotype machine, the combination 105 of the ejector slide C, link D, and actuating lever E, the said lever being provided with the pin F, and the link D being notched at D' to engage the pin and provided with the surface L, together with the longitudinally and pivotally movable latch G connected to the link and formed with the notch J to engage the pin, and formed with the surface K to engage the surface L on the link, and the spring M connected to said latch and link. 110

8. In a typographical machine, the combination of the ejector slide, its actuating lever, the intermediate link detachably connected to the lever, and a latch to prevent positively the disconnection of such parts, the said latch being movable bodily from its operative position to permit their disconnection.

In testimony whereof I have affixed my signature in presence of two witnesses.

RICHARD M. BEDELL.
